(Cl. D87—5)

FIG. 2.

FIG. 3.

FIG. 4.

FIG. 5.

FIG. 1 is a front perspective view of a luggage case embodying our new design, the opposite side and end being similar to those shown;

FIG. 2 is a top plan view of the luggage case of FIG. 1;

FIG. 3 is a bottom plan view of the luggage case of FIG. 1;

FIG. 4 is an end elevation of the luggage case of FIG. 1, broken away at each side to show the configuration of the shells; and

FIG. 5 is a fragmentary section, corresponding to a portion of FIG. 4, but on an enlarged scale.

We claim:

The ornamental design for a luggage case, as shown and described.
